UNITED STATES PATENT OFFICE

WILLIAM W. MCWILLIAMS, OF EAST ORANGE, NEW JERSEY, ASSIGNOR TO WESTERN ELECTRIC COMPANY, INCORPORATED, OF NEW YORK, N. Y., A CORPORATION OF NEW YORK

TOOL FOR HANDLING CLAMPING MEMBERS

Application filed January 8, 1931. Serial No. 507,422.

This invention relates to a tool for handling clamping members, and more particularly to a tool for detaching and removing cable clamping members of the type disclosed in the patent to Bowly et al., No. 1,782,404, issued November 25, 1930.

An object of the invention is to provide a simple and inexpensive tool for handling clamping members of the type above referred to.

The invention contemplates a tool having portions movable with respect to each other, and means responsive to a relative movement between the portions for detaching and simultaneously removing a clamping member. In accordance with one embodiment of the invention there is provided a tool comprising a handled bar or body portion terminating in a removable beveled round ended blade adapted to be inserted between adjacent interlocked clamping members. A slide carried by the body portion is formed with finger grips and is provided with removable spaced hooks for engaging one of the clamping members, thereby cooperating with the beveled blade to detach and remove said clamping member upon a relative movement between the slide and the body portion.

Other features and advantages of the invention will become apparent from the following detailed description, reference being had to the accompanying drawing, wherein

Fig. 1 is a perspective view of a tool embodying the features of the invention, showing one manner in which it may be employed for detaching cable clamping members;

Fig. 2 is a vertical sectional view thereof;

Fig. 3 is a fragmentary section on line 3-3 of Fig. 2 and

Figs. 4 and 5 are enlarged detailed views of the removable blade.

Referring now to the drawing, the reference numeral 10 designates a portion of a cable supporting framework to which a plurality of cables 11, 11 are attached by means

of cooperating interlocked clamping members 12, 12 of the type disclosed in the patent to Bowly et al. hereinbefore referred to. Briefly described, these clamping members consist of flat strip material, preferably sheet metal, formed into a two sided right angle member provided with means for interlocking engagement with each other to attach cables to a supporting framework or to previously attached cables. Each of the clamping members is formed with slots 13 and 14 for accommodating the vertical portion of another similar clamping member. A depending prong 15 extending inwardly within the slot 14 engages one of a plurality of spaced slots 17 in the vertical portion of a similar clamping member to thereby interlock vertically adjacent clamping members. The horizontal portion of each clamping member is provided with a projecting prong 18 for engaging one of a plurality of spaced slots 20, 20 in the horizontal portion of a similar clamping member to thereby interlock horizontally adjacent clamping members.

The tool of the present embodiment of the invention, designated generally in the drawing by the reference numeral 25, is particularly designed for facilitating the removal of the above described cable clamping members as for example, when it is desired to remove or rearrange the supported cables. Referring to Figs. 1 and 2 of the drawing, it will be observed that the tool consists of a bar or body portion 26 provided at one end with a handle or knob 27 and terminating, at its opposite end, in a slightly bent tapered portion 28 (Fig. 2) having a removable blade 29 attached thereto by means of a clamping plate 30. As shown in Figs. 4 and 5, the blade 29 terminates in a beveled round ended portion 32 to facilitate its insertion between the depending prong 15 of one clamping member and the slotted vertical portion of an adjacent clamping member. A slide 35 carried by the body portion 26 of the tool is formed

with finger grips 36—36 and is provided with spaced hooks 37—37 for engaging the slot 14 of the clamping member on opposite sides of the depending prong 15, as shown in Figs. 2 and 3. The hooks 37 are removably attached to the slide 35 by means of a clamping plate 38. Obviously, the removable blade 29 and hooks 37 may be replaced when worn at a very small cost, thus lengthening the life of the tool.

In the operation of the above described tool, the knob 27 is grasped by the palm of the hand and the slide 35 is gripped by the first two fingers of the same hand. The hooks 37 are then engaged with the slot 14 of the clamping member to be removed and the beveled blade 29 is inserted between the depending prong 15 of said clamping member and the slotted vertical portion of the adjacent clamping member. The knob 27 and slide 35 are then pressed toward each other to move the blade 29 and hooks 37 away from each other, thereby forcing the blade underneath the depending prong 15 of the clamping member to be removed and thus lifting the prong from locking engagement with the cooperating slot 17 of the adjacent clamping member, the first mentioned clamping member being thereafter removed from the adjacent clamping member by a continued relative movement between the body portion 26 and the slide 35.

It is to be understood that the embodiment of the invention herein illustrated and described is merely illustrative of one useful application of the invention which is capable of numerous other applications within the scope of the appended claims.

What is claimed is:

1. A tool for handling clamping members, comprising a handled bar terminating in a bent portion, a removable blade carried by the bent portion, and means movable with respect to the blade for engaging a clamping member.
2. A tool for handling clamping members, comprising a handled bar, a blade removably carried thereby having a bent portion terminating in a beveled round end, a slide carried by the bar, and means carried by the slide for engaging a clamping member.
3. A tool for handling clamping members, comprising a body portion having a handle at one end thereof and a removable beveled round ended blade at its opposite end, a slide carried by the body portion and having finger grips extending on opposite sides thereof and a pair of spaced removable hooks carried by the slide.
4. A tool for disengaging clamping members, comprising a handle bar, a blade attached thereto so that the bladed portion is parallel to the handled bar, slidable means carried by the bar and having oppositely projecting

wings integral therewith, and a hook attached to the slidable means.

5. A tool for disengaging clamping members, comprising a handled bar terminating in a bent portion, a blade having a bent portion and attached to the bar so that the bladed portion is parallel to the handled bar, slidable means carried by the bar and having oppositely projecting wings integral therewith, and a hook attached to the slidable means.

In witness whereof, I hereunto subscribe my name this 29th day of December, A. D. 1930.

WILLIAM W. McWILLIAMS.
